UNITED STATES PATENT OFFICE

2,472,446

RAILWAY RAIL JOINT

George A. Standfast, Jefferson City, Mo.

Application September 19, 1947, Serial No. 775,100

1 Claim. (Cl. 238—230)

1

This invention relates to a railway rail joint, and particularly to such joints of the type known as a scarf joint.

Scarf and lap joints for railway construction have been heretofore proposed for the purpose of minimizing the jolting which occurs at common "butt" joints when one rail has moved to a position slightly higher or lower than the rail to which it is joined.

Although such constructions have long since been proposed, they have not proved to be satisfactory in service for many reasons. They have tended to weaken the rails at a critical point, and where it has been sought to remedy this fact by introducing reinforcing elements at the joints, the construction has become complicated, and the cost prohibitive. For these and other reasons, the common "butt" joint has remained the standard practice in railway construction.

It is among the objects of the present invention to overcome the difficulties heretofore encountered in railway rail joints of the type to which the invention relates, and provide a joint of the scarf or lap type which is simple in construction, and which will leave the rail at the joint fully as strong as the common "butt" joint.

The foregoing and other objects and features of the invention will be made fully apparent to those skilled in the art from a consideration of the following detailed description taken in conjunction with the accompanying drawings, in which:

Figure 1 is a perspective view of a rail joint constructed in accordance with the present invention;

Figure 2 is a longitudinal cross-section through a rail joint;

Figure 3 is a top plan view of the same;

Figure 4 is a transverse cross-section taken on the line 4—4 of Figure 3;

Figure 5 is a detail top plan view of a fragmentary portion of the rail joint showing the manner of dressing the pointed ends of the rail head;

Figure 6 is an elevation of a fragmentary portion of a rail further showing the manner of dressing the flange end of the rail head; and

Figure 7 is a transverse cross-section on the line 7—7 of Figure 3 showing the manner in which a car or locomotive wheel contacts the improved rail joint.

In the drawings, reference numerals 10 and 11 indicate rail sections which are joined in accordance with the present invention. The rail sections 10 and 11 are common type T-rails, each having a flange 12, a web 13, and a head 14. The

ends of each rail are cut off at an angle of approximately 45° in a plane substantially perpendicular to the bottom surface of the flange, the cuts being always made in the same direction, so, that if one of the rails, for example 11, were turned around, its opposite end would still match with the end of the rail 10, as shown. The two rail sections so cut are joined by means of a pair of conventional fish plates 15, one on each side of the web 13, and bolts 16 extend through the fish plates and through suitable openings in the web 13 to be secured at their threaded ends by nuts 17. It will be observed that at the center of the rails, the gap between the two rail sections lies equidistant between the two adjacent inner bolts and that at the outer surfaces of the web 13 the ends of the gap, while lying closer the inner bolts 16, will nevertheless be well spaced from such bolts. Each of the bolts 16 extends through only one of the rail sections 10 or 11 and the 45 degree or miter cut on the ends of the rails keeps the tension forces on bolts 16 within safe limits under rail expansion conditions since at least half of the expansion force is carried directly by the rail ends.

25 The tip of each rail head 14 is dressed off, as indicated at 18 to an inwardly tapered condition. The taper extends for a distance of about five-eighths inch in the direction of the length of the rail head at its deepest portion, and is about one-eighth inch deep at the end of the rail head. The taper extends around the curved edge of the top of the rail head, as illustrated in Figure 5, and downwardly along the side of the head 14 to, but not below, the inwardly curving oval edge at the bottom thereof as illustrated in Figure 6, the broken line in this figure indicating the original extent of the toe portion of the rail head end before inwardly tapered as shown in full lines. Figure 7 illustrates the manner in which the wheels and wheel flanges cooperate with the improved rail joint. The inwardly tapered portions 18 prevent the pointed end or toe a of one rail end from projecting outwardly beyond the heel b of the adjacent rail end, even when the rails are under a condition of maximum expansion, so that the tips of the toe portions are not bent or chipped by the pressure of the wheel flanges c thereon, as is clearly shown in Figure 7. The taper thus provided on the toe portion of a rail head end extends around the upper rounded edge and down the inner side of the head over the area of the head tip subject to contact by the wheel flange, but does not extend beyond this area in order that the taper will not require the removal of any more

metal than is absolutely necessary from the rail head.

While, for convenience in assembling the rails, all of the rail head toe portions may be tapered, it is necessary to taper only those toe portions at that side of a connected rail assembly facing the parallel rail assembly of a two-rail track.

The toe or corner portions of the rail flanges 12 are cut back for about one inch to remove the sharp points and render the rails easier and safer to handle.

In use, the construction above described presents numerous advantages over rail joints of the scarf type, as heretofore proposed. By making the cut at the end of each rail section at an angle of about 45°, the lapping portions of the two rail sections are much shorter than in prior constructions. The cut does not extend through any of the bolt holes in the webs of the rails, and thus the rails are not weakened at this critical point. When the rails expand in hot weather, the two rail sections may come into abutment with little or no wedging action of the overlapping portions against the fish plates. Where these cuts are made at a higher angle, the lapping portion of one rail functions as a wedge, acting to pry the fish plate outwardly from the rail. In the present construction, the angle at which the cut is made is sufficient to attain the advantages of lap or scarf joints, but is below the angle at which the rails will slide upon each other after expansion into abutting relation, and thus the objectionable wedging action is reduced. At the same time wheel pressure and other factors may cause adjacent rail ends to move laterally relative to each other and by inwardly tapering the toe portions

of the rail heads the tips of the toe portions are made stronger and do not at any time project outwardly beyond the adjacent rail head heel portions and are thus protected from damage by the wheel flanges regardless of the direction of traffic on the rails.

Having thus described the invention, I claim:

In a scarf-joint, railway rail comprising a flange, a web and a rail head having upper and lower rounded edges, said rail having its end surfaces disposed in respective planes substantially perpendicular to the bottom surface of said flange and inclined substantially 45° to the longitudinal center line of the rail, and said rail head having 10 at each end thereof an acute toe and having on its outer side at the end of each toe a surface inclined upwardly and inwardly from the bottom curved edge of said side to a location disposed inwardly of the adjacent upper curved edge and 15 inclined outwardly from the end of said toe to the surface of said side at a location spaced from the end of said toe.
